(57) **CLAIM**

The ornamental design for a sponge mop head, as shown and described.

DESCRIPTION

FIG. 1 is a perspective view of a sponge mop head showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a top plan view thereof with the support base of the mop head removed to show the plates; and,

FIG. 8 is a perspective view of the sponge mop head of FIG. 1, the broken line showing of a portion of the sponge mop is for illustrating an environment of the design and forms no part of the claimed design.

The broken line showing of the support base of the mop head and holes in the plates in FIGS. 1–7 are for illustrative purposes only and form no part of the claimed design.

1 Claim, 7 Drawing Sheets
